US0D1048096S

(12) **United States Design Patent** (10) Patent No.: **US D1,048,096 S**
(45) Date of Patent: ** Oct. 22, 2024

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gregory M. Apodaca**, Colbert, WA (US); **Kristin M. Canavan**, San Francisco, CA (US); **Pablo F. Caro**, San Francisco, CA (US); **Chanaka Karunamuni**, San Jose, CA (US)

(73) Assignee: **Apple Inc.**, Cupertino, CA (US)

(**) Term: **15 Years**

(21) Appl. No.: **29/852,146**

(22) Filed: **Sep. 2, 2022**

(51) LOC (14) Cl. **14-04**

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

**1 Claim, 1 Drawing Sheet
